UNITED STATES PATENT OFFICE.

WYMAN N. HILL, OF EAST HAMPTON, CONNECTICUT, ASSIGNOR TO THE N. N. HILL
BRASS CO., OF EAST HAMPTON, CONNECTICUT, A CORPORATION.

WHEELED TOY.

Application filed May 9, 1928. Serial No. 276,388.

This invention relates to improvement in wheeled toys and particularly to wheeled toys provided with gongs which will ring as the toy is rolled forward or backward. 5 The object of this invention is to provide an attractive toy with a hoop and figures arranged to pass through the hoop as the toy is moved, and the invention consists in the construction as hereinafter described and particularly recited in the claims.

In the accompanying drawings:

Fig. 1 is a front view of a wheeled toy constructed in accordance with my invention;

Fig. 2 is a side view with one of the wheels 15 partly broken away; and

Fig. 3 is a transverse sectional view on an enlarged scale.

In carrying out my invention, I employ two wheels 5 and 6 mounted upon an axle 7 20 in the form of a bolt with a nut 8 at one end. Mounted on the axle are two crossed bars 9 and 10 and secured to the ends of the rods are figures 11 of any desired character. Preferably, one of the bars is struck inward 25 to form nubs 12 to enter recesses 13 formed in the other bar, whereby the bars are interlocked together and at right angles to each other. Mounted on the axle and on opposite sides of the bars are spacing-blocks 14 and 30 15 and beyond these blocks on either side are two reversely-arranged gong-bells 16 and 17 between which are spacers 18 and 19 of proper length to separate the edges of the gongs and within the gongs are strikers 20. Beyond 35 the gongs are filling-blocks 21 and 22, these being all held in position with respect to the wheels by the bolt 7. Mounted on the filling-blocks 21 and 22 is a bail 23 to which a cord 24 may be attached, whereby the toy may be 40 trundled.

Loosely mounted on the spacing-blocks 14 and 15 is a strip of metal 25 doubled at the center to form an open hoop 26 and provided at its lower ends with eyes 27 for the attachment of weights 28.

When a toy thus constructed is moved back or forth, the wheels turn the axle and with

it the bars 9 and 10 and so cause the figures carried by these bars to pass through the hoop 26, the hoop being held in substantially vertical position by the weights 28. As the toy is moved, the strikers 20 fall against the bells so as to produce sounds.

It is obvious without illustration that a single bar may be employed, or more than two bars, in case of larger toys, and while I have shown the representation of horses on the ends of the bars, it is obvious that any desired figures may be so employed. This construction provides a very attractive and 60 fascinating toy for children.

I claim:

1. A wheeled toy, comprising a pair of wheels mounted upon an axle, a bar connected with said axle so as to turn therewith, a figure on each end of the said bar, and an open hoop having leg portions loosely mounted on the axle on opposite sides of the bar connection and arranged for the passage of the bar or bars and the figures on the said 70 bar.

2. A wheeled toy, comprising a pair of wheels mounted upon an axle, a bar on said axle, spacing-blocks on each side of and clamping the bar, whereby the bar is connected 75 with said axle so as to turn therewith, a figure on each end of the said bar, an open hoop having leg portions loosely mounted on the axle on opposite sides of the bar connection and arranged for the passage of the bar or 80 bars and the figures on the said bar.

3. A wheeled toy, comprising a pair of wheels mounted upon an axle, a pair of crossed bars interlocked together and mounted on the axle so as to turn therewith, a figure on each end of the said pair of crossed bars, and an open hoop having leg portions loosely mounted on the axle on opposite sides of the bar connection and arranged for the passage of the bar or bars and the figures 85 on the said bar.

In testimony whereof, I have signed this specification.

WYMAN N. HILL.
